CLAIM

What is claimed is the ornamental design for a self-protecting/ornamental windmill, as shown and described.

DESCRIPTION

FIG. 1 is a front elevation view of the self-protecting/ornamental windmill of applicant's invention.

FIG. 2 is a rear elevation view of the self-protecting/ornamental windmill of applicant's invention.

FIG. 3 is a left side elevation view of the self-protecting/ornamental windmill of applicant's invention.

FIG. 4 is a right side elevation view of the self-protecting/ornamental windmill of applicant's invention.

FIG. 5 is a top view of the self-protecting/ornamental windmill of applicant's invention.

FIG. 6 is a bottom view of the self-protecting/ornamental windmill of applicant's invention; and,

FIG. 7 is a left side elevation view of the self-protecting/ornamental windmill of applicant's invention on a reduced scale, with the attachment to the end post in open position, the opposite side being a mirror image of that shown.

The end post has been shown broken away in FIGS. 1-4 and 7 to indicate indeterminate length.
